UNITED STATES PATENT OFFICE.

JOHN P. HOPPERT, OF BALTIMORE, MARYLAND.

PORABLE HEATER.

SPECIFICATION forming part of Letters Patent No. 613,514, dated November 1, 1898.

Application filed March 9, 1898. Serial No. 673,218. (No model.)

To all whom it may concern:

Be it known that I, JOHN P. HOPPERT, residing in the city of Baltimore and State of Maryland, have invented a new and Improved Portable Heater, of which the following is a specification.

This invention is in the nature of a simple and economical portable heating device, more especially adapted for use to generate heat within the fire part of a range during hot weather or at other times when it is not desirable to build a fire therein, whereby to heat the water-back or circulating-pipes to obtain hot water in the boiler for bathing and other domestic purposes.

This invention, among other objects, has for its purpose to provide a heating device of this character of a very simple and economical construction which can be readily set in position in the ash-pit or fire-pot of the stove and which will with an economical supply of gas effectively serve to quickly heat the water-back to generate hot water.

The invention consists in a heating device embodying the peculiar combination and novel arrangement of parts, such as will be first described in detail and then be specifically pointed out in the appended claim, reference being had to the accompanying drawings, in which—

Figure 1 illustrates my invention as in use. Fig. 2 is a plan view of my improved heater, parts being in section.

In the practical construction my improvement comprises a feed-pipe which consists of a number of sections 1, having ends 1^a, joined by T-couplings 2, the number of such sections and couplings depending on the size or the length of the fire-pot of the range or water-back to be heated, it being obvious that the number of such sections may be readily increased or decreased, the last or end section having a closure 3 in the nature of a T, which in practice is secured to the end section and adjusted at right angles to the length of the feed-pipe, so as to form a rest or support to hold the burner in a vertical position when the same is held in the ash-pit at a point beneath the water-back, as shown in Fig. 1.

50 The first or front section 1 connects with the angle-union 5, to which is joined a nipple 4, which in the practical application of the in-

vention extends outside the ash-pit and receives the end of the flexible supply-pipe 6, which in turn connects with the gas-jet. 55

To each of the T-couplings 2 is secured a lateral 7, having its end threaded at 7^a and terminating in cone-discharges, having each a pin-orifice 7^b for the escape of the gas. To the conical end of each lateral 7 is detachably secured a burner-section, which consists of a hollow cone-shaped mixing-tube 8, largest at its outer end and smallest at its point of connection with the lateral 7, onto the threaded end of which it is fitted. At a point over the discharge of the lateral 7 the burner-sections 8 have opposing circular openings 8^a, facing lengthwise of the heater, through which the air passes into the burner, it being understood that by contracting the burner at the 70 openings 8^a the air is caused to more readily commingle with the gas as it passes from the lateral 7 in pin-jets.

So far as described it will be readily seen that by placing the device on the ash-pit and holding it so the ends of the burners will discharge against the lower edge of the water-back and turning on the gas-supply to the laterals and igniting it at the pin-jets the air as it is drawn into the heaters through the 80 openings 8^a is consumed with the gas in such a manner as to generate more heat with but a minimum amount of gas consumption and the flame discharged directly against the lower part of the water-heater, thereby concentrating the heat volume at the point to obtain the very best results. Furthermore, by making the closure end 3 adjustable the same can be readily drawn in line with the tubes 8, and when in such position the heater can 90 be laid flat on the grate, as indicated in dotted lines in Fig. 1. When in this position, it is obvious that the flame will also be discharged directly against the lower, but at this time the front, face of the water-back. 95

When used in the fire-pot, it will be understood the nipple end of the heater may be projected down through the grate and out through the ash-pit door for the convenient attaching of the gas-supply pipe. 100

From the foregoing description, taken in connection with the drawings, it is thought the advantages of my invention will be readily apparent. It will be observed that the same

can be quickly and conveniently placed in position either in the ash-pit or in the fire-pot, the end member 3 forming a suitable support for holding the heater in the proper vertical 5 position when the same is placed within the ash-pit.

Having thus described my invention, what I claim, and desire to secure by Letters Patent, is—

- 10 As a new article of manufacture; a portable heater for water-back stoves; comprising a main feed-pipe formed of a series of pipe-sections joined by T-couplings, one end section having an adjustable T-shaped closure member, said T-shaped couplings having the right-angle member detachably connected and terminating at the outer end in a conical pin-discharge; burners detachably secured over the conical ends of the T-laterals, said burners 15 being in the nature of tubes having their
- 20

outer or discharge ends flattened and having oppositely-disposed air-tight openings adjacent the coupling-laterals, and an adjustable nipple secured to the front section of the feed-pipe, all being arranged substantially as 25 shown and described, whereby by turning the T-closure at right angles to the projection of the tube-laterals the device can be supported in the ash-pit with its burner-tubes projected toward or between the grate-bars, and when 30 turned in line with such tubes admit of the device being laid flatwise on the top of the grate-bar with its nipple projected down through the grate-bottom, as and for the purposes specified.

JOHN P. HOPPERT.
